Primary Examiner — Cynthia Ramirez*Assistant Examiner* — Michael A Maharajh*(74) Attorney, Agent, or Firm* — The Webb Law Firm**(57) CLAIM**

The ornamental design for a folding exerciser equipment, as shown and described.

DESCRIPTION

FIG. 1 is a front elevation view of a folding exerciser equipment showing my new design;

FIG. 2 is a rear elevation view thereof;

FIG. 3 is a left side elevation view thereof, the right side elevation view being a mirror image thereof;

FIG. 4 is a top view thereof;

FIG. 5 is a bottom view thereof;

FIG. 6 is a front perspective view thereof; and,

FIG. 7 is a rear perspective view thereof.

The broken lines shown in the figures are for the purpose of illustrating portions of the folding exerciser equipment, which form no part of the claimed design.
